UNITED STATES PATENT OFFICE.

LOUIS SEVERUS, OF CHICAGO, ILLINOIS.

ELECTRIC-LIGHT FIXTURE.

1,114,299.

Specification of Letters Patent. Patented Oct. 20, 1914.

Application filed May 27, 1912. Serial No. 699,884.

To all whom it may concern:

Be it known that I, LOUIS SEVERUS, a citizen of the United States, and a resident of Chicago, in the county of Cook and State of Illinois, have invented certain new and useful Improvements in Electric-Light Fixtures, of which the following is a full, clear, and exact description.

The invention relates to electric-light fixtures.

It is now common practice to provide porcelain jackets which resemble candles in appearance, with electric lamps at their upper ends, in order to provide electric light fixtures in harmony with the furnishings or finish of a room. Generally these incandescent lamps are mounted in a socket supported in the upper end of a tube which was cut according to the height of the jacket. In cutting the tubes, or in the use of non-adjustable fixtures for supporting the lamp, it frequently occurred that the lamp was not sustained in correct relation to the jacket in order to give the desired effect, due to inaccuracy in fitting and to variation in the length of the porcelain jackets which cannot be readily cut by the fitter in installing the fixtures.

The present invention designs to provide an improved fixture which is adapted to be secured to the end of a pipe through which the conductors pass and which adjustably supports the lamp-socket, so that the socket may be set and held at different distances from the terminal of the pipe, and in the exact relation desired relatively to the upper end of the porcelain-jacket. By providing this adjustable support for the lamp-socket which is adapted to be housed in the porcelain-jacket, the support is adapted to serve for use in jackets of different heights.

Another object of the invention is to provide an improved lamp-socket support which may be extended or adjusted so that the lamp will be supported in the desired relation to the upper end of the jacket, and which may be used with jackets of different heights or lengths.

The invention consists in the novel features hereinafter set forth and more particularly defined by claims at the conclusion hereof.

In the drawings: Figure 1 is a side elevation of a fixture embodying the invention. Fig. 2 is a central vertical section. Fig. 3

is a side elevation of the improved support. Fig. 4 is a section taken on line 4—4 of Fig. 2.

10 denotes a pipe-terminal of usual construction, which is provided with a screw-thread 11 at its upper end and a cup or base 12 rests upon a shoulder 13 on said terminal. The electrical conductors 14 and 15 are extended through pipe 10. Conductor 14 has its upper end connected by a screw 16 to the screw-threaded shell 17 of an incandescent-lamp socket 18 which is adapted to receive the base of an incandescent lamp 19 of usual construction. Conductor 15 is connected by a screw 20 and a strip 21 to the tip-contact 22 which is adapted to contact with tip 22^a of the lamp base. The body 23 of the lamp-socket in which shell 17 and the contact-connections are supported, is formed of insulating material, usually porcelain, and a stud 24 secured in the lower end of said body is provided with a screw-thread 25.

The improved extensible support 27 for the lamp-socket comprises two members, 28 and 29 which are slidably fitted together, member 28 fitting in a channel formed between ribs 30 on member 29. A screw 31 extends through an elongated slot 32 into member 28 and is adapted to clamp the members securely together. Member 28 has an internally threaded sleeve or boss 33 which is adapted to engage the screw-thread 11 on pipe-terminal 10 to secure the support 27 to the pipe 10. The other member 29 of the extensible support is provided with a screw-thread which is adapted to engage the thread 25 on stud 24 which is secured in the body of the lamp socket 18. A porcelain jacket 36 fits into the cup 12 and extends around the support 27, the lamp-socket, and the conductor wires, thus concealing the entire supporting structure.

In installing the fixture, the screw-thread 25 of the socket 18 is connected to the screw-thread in member 29 to secure the socket to the upper end of the support. The sleeve 33 is then turned on screw-thread 13 of the pipe-terminal 10 to secure the support on the pipe-terminal and to secure the cup 12 thereon. Member 29 may then be adjusted to the desired height to bring the socket into the desired elevation so that it will be properly positioned relative to the top of jacket 36 so that the lamp will be supported in its desired position. The conductor-

wires are then connected to the contact-terminals 16 and 20 and the jacket 36 slipped in place around the support socket and wires. The lamp will then be secured in the socket. Obviously, the support may be adjusted to bring the lamp exactly into the desired position relatively to the jacket, by adjusting member 29 on member 28 of support 27.

- 10 Important advantages of the invention are that the adjustable support for the lamp-socket is adapted for holding incandescent lamps in the proper position above porcelain jackets of different heights, that it 15 overcomes any irregularity due to variation in the length of the jacket, and that it also permits the socket to be adjusted into proper relative position with respect to the jacket, according to the shape of the lamp used. 20 Thus, the invention avoids the necessity of specially fitting a support to the pipe-terminal in order to support the socket in the desired position relatively to the top of the porcelain jacket. Upon removal of the 25 jacket, the conductors will be readily accessible for repair.

The invention is not to be understood as restricted to the details set forth, since these may be modified within the scope of the appended claims without departing from the 30 spirit and scope of the invention.

Having thus described the invention,

what I claim as new and desire to secure by Letters Patent, is:

1. An electric light fixture, comprising a 35 pipe-terminal, an incandescent lamp-socket, an extensible support between the socket and said pipe-terminal, and a jacket around said support, said support comprising a pair of bars at one side of the jacket slidably and 40 adjustably connected to each other at one end and bent inwardly at the other, said inwardly bent ends being provided with a screw-thread for connection to the pipe-terminal and to the socket respectively. 45

2. An electric-light fixture comprising a pipe terminal, an incandescent lamp-socket, a pair of conductors leading from the terminal to the socket, a stud in said socket at the lower end thereof, an extensible support 50 comprising a pair of bars each provided with a screw-thread for connection to the pipe-terminal and to the stud on the socket respectively, said bars being offset intermediate their points of connection to the pipe-terminal and to the sockets respectively to permit the conductors from the terminal to align with the socket and to be readily adjusted without interference by said support, and a jacket around said support. 55

LOUIS SEVERUS.
